Bennett K. Benson

UNITED STATES PATENT OFFICE.

BENNETT K. BENSON, OF HATTON, NORTH DAKOTA.

JEWELRY-SETTING.

1,344,111.

Specification of Letters Patent. Patented June 22, 1920.

Application filed December 21, 1918. Serial No. 267,748.

To all whom it may concern:

Be it known that I, BENNETT K. BENSON, a subject of the King of Great Britain, residing at Hatton, in the county of Traill 5 and State of North Dakota, have invented certain new and useful Improvements in Jewelry-Settings, of which the following is a specification.

This invention relates to new and useful 10 improvements in jewelry for personal adornment and more particularly to an improved setting for finger rings, scarf pins, brooches, cuff-links and other articles of jewelry.

15 The primary object of the invention is to provide a flat plate or panel adapted to be rigidly attached to a supporting means whereby the panel may be suitably inscribed or set with an ornamental insignia so that 20 the inscription or insignia will have a neat and ornamental appearance.

The invention also includes an arrangement whereby the panel is rigidly attached to the supporting element so that casual or 25 accidental displacement of the display panel is prevented.

A further object of the invention is to 30 provide a device of this character which consists of comparatively few parts and is simple in construction, but durable and well adapted to withstand the rough usage to which devices of this character are ordinarily subjected.

For a full description of the invention 35 and the advantages and merits thereof, reference is to be had to the following description and accompanying drawings, in which:—

Figure 1 is an edge elevation of a finger 40 ring showing my invention applied thereto.

Fig. 2 is a section taken on the line 2—2 of Fig. 1.

Fig. 3 is a plan view of the ring constructed in accordance with my invention.

45 Fig. 4 is a section taken on the line 4—4 of Fig. 3.

Fig. 5 is an edge view of a slightly modified form of the invention.

Fig. 6 is a section taken on the line 6—6 50 of Fig. 5.

Referring to the drawings, in which is illustrated the preferred form of my invention, in which like numerals of reference indicate corresponding parts throughout the 55 several views, the loop 1 is constructed of suitable metal such as is commonly em-

ployed for making finger rings and is shaped to fit the finger upon which the ring is to be mounted. The loop 1 is shaped to provide the spaced apart retaining bars 2 60 which are disposed tangentially with respect to the main portion of the ring and lie in parallel relation. The ends of these retaining bars 2 converge and are joined together at the opposite ends thereof at which 65 point they are integrally joined with the finger receiving loop 1. The straight portions of the retaining bars 2, however, may be of any desired length.

A pair of plates 3 and 4 are provided and 70 may be constructed of ivory, jet, gold, silver, or any other similar material employed for making jewelry. These plates 3 and 4 are preferably of rectangular formation to present comparatively large flat surfaces. The 75 plate 4 is superimposed on the plate 3 and the two contacting surfaces are cemented or otherwise securely fastened together. The contacting surface, in each plate, however, is provided with parallel grooves or recesses which extend from one edge to the other of the plate and when the two plates are fastened together as shown to advantage 80 in Fig. 4 of the drawings, the grooves or recesses provide openings extending edgewise 85 through the panel formed by the two plates. The plates are of the same width as the length of the straight portions of the retaining bars 2 so that the retaining bars begin to converge at opposite edges of the 90 plate and any movement of the plate on the retaining bars is thereby prevented.

The two plates 3 and 4 are rigidly cemented together and the upper surface of the panel thus formed presents a suitable 95 display surface upon which may be inscribed any desirable inscription or which may receive a suitable setting or insignia. The loop 1, of course, might be in the form of a fastening pin such as is employed for 100 scarf pins or brooches, and might also be a cuff link, it being merely necessary to so construct the member 1 as to provide the two parallel spaced apart retaining bars 2 of the desired length.

In Figs. 5 and 6 I have illustrated a slightly modified construction of the finger engaging loop, which in this instance, is constructed of twisted wire, portions of which are spaced apart and held in parallel 110 relation to form the retaining bars 2' which extend through the grooves in the plates 3'

and 4' in the same manner as is above described. This modification will illustrate one of the various modifications with which the two plates forming the panel may be employed.

5 The foregoing description and accompanying drawings have reference to what might be considered to be the preferred or approved form of my invention. I desire it to be understood, that I may make such corrections in the combination, construction and arrangement of parts, materials, dimensions, et cetera, as may prove expedient and fall within the scope of the 10 appended claims.

Having thus fully described my invention what I claim as new and desire to secure by Letters Patent, is:—

1. A jewelry mounting comprising means 20 for attaching the mounting to the person, the said means including a pair of spaced apart parallel retaining bars of predetermined length, a pair of connecting plates of a width equal to the length of the parallel portions of the said retaining bars, the proximate surfaces of the said plates being provided with complementary grooves, the said plates having their contacting surfaces secured together whereby the said complementary grooves form openings extending edgewise through the panel formed by the said plates, the said retaining bars being mounted in the said openings and relatively connected exteriorly of said opening to prevent movement of said plate on said bar.

2. A jewelry mounting comprising a finger loop having a pair of laterally spaced apart parallel retaining bars having their adjacent ends relatively joined to provide a 40 unitary looped structure, a flat panel provided with openings extending edgewise through the plate and receiving the said

spaced retaining bars, the said panel comprising united plates provided with complementary grooves forming the said openings, the joined ends of said retaining bars providing abutments preventing movement of said panel on said bars. 45

3. A jewelry mounting comprising a supporting unit adapted for attaching the 50 mounting to a person and a panel consisting of upper and lower sections provided with complementary grooves to form a pair of passages, said panel supporting unit including oppositely disposed forked portions branching out laterally beyond both sides of the supporting unit and relatively connected by laterally spaced parallel portions, said connecting portions adapted to be respectively accommodated within the passages of the 55 60 said panel.

4. A jewelry mounting including a one-piece support having spaced, forked portions the branches of which face toward each other, a panel having spaced, separate 65 passages therethrough and spaced parallel panel supporting members separately joining the branches of one forked portion to the branches of the adjacent forked portion, whereby a suitable panel receiving face is 70 provided between the forked portions of said one-piece support, said forked-connecting members adapted to respectively be received within the separate passages of said panel, whereby the latter may be immovably 75 supported between the forked portions of said support.

In testimony whereof I affix my signature in presence of two witnesses.

BENNETT K. BENSON.
